United States Patent Office

Des. 211,464
Patented June 18, 1968

211,464

CHAIR OR THE LIKE

Warren Platner, North Haven, Conn., assignor to Knoll
Associates, Inc., New York, N.Y., a corporation of New York

Original design application Aug. 31, 1965, Ser. No.
86,788. Divided and this application July 17, 1967,
Ser. No. 8,769

Term of patent 14 years

(Cl. D15—1)

Fig. 1.

Fig. 2.

Fig. 3.

Fig. 4.

FIG. 1 is a front perspective view of a high-back chair embodying the new design.

FIG. 2 is a side perspective view of the high-back chair of FIG. 1.

FIG. 3 is a rear perspective view of the high-back chair of FIG. 1.

FIG. 4 is a sectional view of the high-back chair shown in FIG. 3, on an enlarged scale taken along the section line 4-4 of FIG. 3 and looking in the direction of the arrows.

The side of the article not shown is a mirror image of the side shown.

This application is a division of my copending application, Ser. No. D. 86,788, filed Aug. 31, 1965, for an article of furniture.

I claim:

The ornamental design for a chair or the like, as shown and described.
